United States Patent Office

Des. 202,220

Patented Sept. 7, 1965

202,220

DECANTER AND CLOSURE THEREFOR

Ernest L. Du Pree, New York, N.Y., assignor to Schenley
Industries, Inc., New York, N.Y., a corporation of
Delaware

Filed June 10, 1964, Ser. No. 80,347

Term of patent 14 years

(Cl. D58—6)

FIG 3

FIG 4

FIG 5

FIG 6

FIGURE 1 is a front elevational view of a decanter and closure therefor embodying my new design;

FIGURE 2 is a rear elevational view of the decanter shown in FIGURE 1;

FIGURE 3 is a side elevational view of the decanter and closure therefor shown in FIGURE 1;

FIGURE 4 is a top plan view of the decanter and closure therefor shown in FIGURE 1;

FIGURE 5 is a top plan view of the decanter shown in FIGURE 2;

FIGURE 6 is a bottom plan view of the decanter shown in FIGURE 2;

FIGURE 7 is a longitudinal sectional view, taken on the line 7—7 of FIGURE 4;

FIGURE 8 is a transverse sectional view, taken on the line 8—8 of FIGURE 3;

FIGURE 9 is a transverse sectional view, taken on the line 9—9 of FIGURE 3;

FIGURE 10 is a transverse sectional view, taken on the line 10—10 of FIGURE 3; and

FIG 8

FIG 9

FIG 10

FIG 11

FIGURE 11 is a transverse sectional view, taken on the line 11—11 of FIGURE 3.

The side of the decanter and closure therefor opposite that shown in FIGURE 3 appears the same as the side shown. The sides of the closure not shown in FIGURES 1 and 3 appear the same as the sides shown.

FIGURES 9, 10 and 11 are shown broken away for convenience of illustration.

I claim:

The ornamental design for a decanter and closure therefor, as shown and described.
